UNITED STATES PATENT OFFICE.

WILLIAM HARTMAN WOODIN, JR., OF PLAINFIELD, NEW JERSEY.

RADIO AERIAL POLE OR THE LIKE.

Application filed August 31, 1925, Serial No. 53,696. Renewed August 10, 1927.

This invention relates to masts or poles for supporting radio aerials and the like, and has particular reference to an all-metal pole and stand or bracket therefor.

5 To that end the invention contemplates a novel supporting stand or bracket which may be readily applied to flat or peaked roofs in such a way that it may be readily adjusted to fit any pitch of the roof thereby 10 to afford a stable and adequate anchorage for the pole. In that connection the invention proposes to provide a stand having structural features which strengthen and reinforce the same and at the same time afford 15 convenient means for attaching the pole or mast, thereby greatly simplifying the erection of the pole, and also providing a construction which is neat in appearance.

A further object of the invention is to 20 provide a durable all-metal construction which may be made from sheet metal parts that may be readily stamped to shape thereby producing an article which is susceptible of production in quantities sufficient to 25 bring about economical manufacturing costs.

With the above and other objects in view which will more readily appear as the nature of the invention is better understood, the same consists in the novel construction, 30 combination and arrangement of parts hereinafter more fully described, illustrated and claimed.

A preferred and practical embodiment of the invention is shown in the accompanying 35 drawings, in which:

Figure 1 is an end elevation of the invention.

Figure 2 is a top plan view of the complete construction.

40 Figure 3 is a side elevation of the lower part of the construction shown in Figure 1.

Figure 4 is a detail perspective view of the pole base.

Similar reference characters designate 45 corresponding parts throughout the several figures of the drawings.

In its general aspect the general invention includes in its organization the stand or bracket designated generally as A and a 50 pole base B attached to the lower end of a pole C.

The said stand or bracket A is of substantially transversely arched formation and has the flat platform surface 1 with depending side wings 2 which are stiffened and reinforced against flexing or bending by the

diagonal reinforcing ribs 3. These ribs 3 are pressed inwardly from the corners of the base A and thereby provide grooves at the outside faces of the top and wings as clearly 60 shown in Figs. 1, 2 and 3, and though these ribs may be used in any desired number and arrangement, it is preferred to locate the same at points where their stiffening effect will be the most useful, namely, adjacent the 65 point of connection between the wings and the roof attaching members 4. These members are preferably in the form of hinge leaves pivotally secured to the lower edges of the wings by the hinge pintles 5 and the 70 fixed leaf 6 which may be riveted, welded or otherwise attached to the wings. While it will of course be understood that the attaching members 4 may be connected to the wings 2 in the manner specified, nevertheless it is within the scope of the invention to 75 pivotally connect the same with hinge knuckles formed from the wings.

The pole or mast C preferably consists of a pair of hollow complementary sections 8—8 80 which are connected by longitudinal flanges which form a closed seam 9 for the greater part of their length, but which are spaced apart as indicated at 10 to provide slots for receiving the key webs 11 of the pole base B. 85 That is to say the pole C is made in two tapering sections which are flanged and connected by welding or the like, to provide the seam 9, whereby the lower open end thereof is adapted to telescopically receive the 90 standing collar portion 12 and webs 11 of the pole base so that when the lower end of the pole is welded to the base a rigid well braced connection is formed.

Referring more particularly to the pole 95 base B it will be observed that the same is preferably made in two sections which when assembled provide the key walls 11 and the pole receiving collar 12 while the ends thereof are bent upwardly as indicated at 13 to stiffen the key walls 11 and also strengthen the base flange 14. The two sections of the base may be readily stamped from sheet metal and may be placed together as shown in Figure 4 and then fitted into the open end of the pole where they may be welded to provide the pole with a rigid footing that may be readily attached to the upper face 1 of the base A by means of the fastenings 15. These fastenings may be inserted through the openings 14^a in the pole base which register with complementary openings 1^a in the 100 105 110

platform 1 of the base. The said fastenings may be screw bolts or the like and by reason of the manner in which the wings 2 hold the platform 1 spaced above the roof it becomes 5 a simple matter to handle the fastenings 15 to properly position them and adjust them in place, and also to detach the same for removing the pole when necessary.

From the foregoing it will be apparent 10 that the present invention provides a novel brace or bracket A having the roof attaching leaves 4 which may be secured to the roof of the building or other surface by means of the fastenings 7, the character of fastening 15 depending of course upon the kind of roof or support to which the device is attached. The diagonal ribs 3 serve to materially reinforce and stiffen the stand and thereby prevent the wings from hinging at the junction thereof with the platform 1. In other words the ribs 3 provide in effect rib-brackets for strengthening the support against lateral collapse. Also, another advantage of 20 the present construction is that it provides 25 a support which permits the free circulation between itself and the roof or other support, thereby preventing rusting and rotting of the parts which might otherwise collect and retain moisture and dampness.

Without further description it is thought 30 that the features and advantages of the invention will be readily apparent to those skilled in the art, and it will of course be understood that changes in the form, proportion and minor details of construction 35 may be resorted to, without departing from the spirit of the invention or scope of the appended claims.

I claim:

1. A support for poles or the like comprising a sheet metal stand having a platform and offset wing portions, and means for connecting the wing portions to a support.

2. A support for poles or the like comprising a sheet metal stand having a platform portion and offset wing portions, diagonal reinforcing ribs formed in the stand between the wings and the platform.

3. A support for poles or the like comprising a sheet metal stand having a flat plat-

form portion and offset wings, hinged leaf members connected to the lower edge portions of the said wings, a pole base adapted to have a bearing on said platform portion, and fastenings for connecting said pole base 55 with the platform portion.

4. A support for poles or the like comprising a sheet metal stand having means for attaching the same to a roof or the like, said pole being hollow and provided with 60 key slots in one end, a pole base having a collar portion adapted to fit into said hollow pole and having key walls fitting into said key slots, and means for attaching said base to said stand.

5. A support for hollow poles or the like, including a stand formed of an arched plate having a plurality of wings hinged to the lower edges thereof, and a pole base having a portion adapted to telescopically fit into 70 the bottom of the pole and provided with flanges adapted to be attached to said arched plate.

6. A support for poles or the like comprising a stand having a horizontal top and 75 depending side portions, and oblique reinforcing ribs reinforcing the stand plate between the said top and sides, attaching leaves pivotally secured to the bottom edges of the side portions, and a pole base comprising an upstanding collar portion adapted to fit into the lower end of a hollow pole and having flanges adapted to be secured to the top of said anchor plate.

7. A support for poles or the like comprising a stand formed from pressed sheet metal into substantially transversely arched cross-section thereby providing a top and depending side walls forming wings, oblique reinforcing ribs formed at the corner angles 90 thereby to stiffen the side walls, roof attaching leaves pivotally secured to the lower edges of said side portions adjacent the location of the reinforcing grooves, and a pole base adapted to be carried by the top of said 95 anchor plate.

In testimony whereof I hereunto affix my signature.

WILLIAM HARTMAN WOODIN, JR.
